UNITED STATES PATENT OFFICE.

JOHN L. SOMMER, OF NEWARK, NEW JERSEY, ASSIGNOR TO J. L. SOMMER MFG. CO.,
A CORPORATION OF NEW JERSEY.

DESIGN FOR A HANDLE FOR BUTTON-HOOKS OR SIMILAR ARTICLES.

48,015.

Specification for Design.

Patented Oct. 19, 1915.

Application filed April 11, 1912. Serial No. 690,173. Term of patent 14 years.

To all whom it may concern:

Be it known that I, JOHN L. SOMMER, a citizen of the United States, residing at Newark, in the county of Essex and State of New Jersey, have invented a new, original, and ornamental Design for a Handle for Button-Hooks or Similar Articles, of which the following is a specification, reference being had to the accompanying drawing, forming part thereof.

The figure is a side view of a button hook, having a handle of my new design.

I claim—

The ornamental design for a handle for button hook or similar article as shown.

JOHN L. SOMMER.
